(57) **CLAIM**

The ornamental design for a retailer for an impression coping, as shown and described.

DESCRIPTION

FIG. 1 is a front elevational view of an impression coping, showing our design, the rear elevational view being a mirror image of the front view shown;

FIG. 2 is a left side elevational view thereof;

FIG. 3 is a right side elevational view thereof;

FIG. 4 is a top plan view thereof, the bottom plan view being a mirror image of the plan view shown;

FIG. 5 is a cross-sectional view thereof, taken along line A—A in FIG. 1; and,

FIG. 6 is a cross-sectional view taken along line B—B in FIG. 3.
